MERCHANDISING DISPLAY STAND FOR LIGHTERS AND THE LIKE

Frank H. Stephens, Jr., Thaddeus I. Kingsford, and Frank
Van Haltern, Jr., Atlanta, Ga., assignors to Scripto, Inc., a corporation of Georgia

Filed June 10, 1965, Ser. No. 85,661

Term of patent 14 years

(Cl. D80—9)

FIG. 1 is a perspective view of the merchandising display stand for lighters and the like embodying our new design;

FIG. 2 is a front elevational view thereof;

FIG. 3 is a side elevational view thereof;

FIG. 4 is a top plan view thereof; and,

FIG. 5 is a rear elevational view of the display stand. We claim:

The ornamental design of a merchandising display stand for lighters and the like, as shown.
